MAURITZ C. INDAHL, OF PHILADELPHIA, PENNSYLVANIA, ASSIGNOR TO LANSTON MONOTYPE MACHINE COMPANY, OF PHILADELPHIA, PENNSYLVANIA, A CORPORATION OF VIRGINIA.

DELIVERING MECHANISM FOR TYPE-CASTING MACHINES.

1,414,472.

Specification of Letters Patent.

Patented May 2, 1922.

Application filed November 9, 1920. Serial No. 422,766.

To all whom it may concern:

Be it known that I, MAURITZ C. INDAHL, a citizen of the United States, and a resident of Philadelphia, county of Philadelphia, and

5 State of Pennsylvania, have invented certain new and useful Improvements in Delivering Mechanism for Type-Casting Machines; and I do hereby declare the following to be a full, clear, and exact description

10 of my invention, reference being had to the accompanying drawings, forming a part of this specification, and to the characters of reference marked thereon.

My invention relates to the handling of 15 type, more particularly as a part of a type-casting machine, in which types after being cast in a mold are ejected therefrom and carried to a type channel and therefrom deposited in a galley or similar receptacle.

20 The object of my invention is, generally speaking, to provide a mechanism by which the type grasping jaws of the device, commonly called a type-carrier, for conducting the type from the mold where it is cast into

25 proximity to the type channel may be adjustably opened to correspond with the point-size of the type bodies being cast in the mold. Another object is to connect such jaw adjustment with the adjustment of the type 30 channel so that the single adjustment of the adjustable type channel block for a particular point size will accomplish a corresponding adjustment of the jaws of the carrier. Another object of my invention is to pro-

35 vide mechanism by which a definite opening of the carrier jaws is maintained in proximity to the matrix seat on the mold whereby, when a type is ejected from the mold between the jaws of the carrier, the latter will

40 not close upon it until the carrier has moved the type away from the region of the matrix seat, thus preventing the breaking off of kerns or other projecting portions from the face of the type. Other objects will be here- 45

inafter more particularly pointed out or will otherwise appear in connection with the following description of the invention as disclosed in the accompanying drawings in which—

50 Fig. 1 is a plan view of a portion of a well known type-casting machine showing particularly the type-delivery mechanism and embodying a form of the present invention.

Fig. 2 is a similar view with the type-de-

livery mechanism adjusted to a different 55 type-size point-wise.

Fig. 3 is an elevation of the mechanism shown in Fig. 1, and

Fig. 4 is a perspective view of the type-carrier, the adjustable channel block, the 60 slide, the connection between the adjustable channel-block and the type-carrier and other related parts.

The type-casting machine, a portion of which is shown in the drawing is the well-known product of Lanston Monotype Machine Company; the general organization of

such a machine is disclosed in Patent No. 625,998, dated May 30, 1899, and the general construction of the improved type-carrier 65 illustrated herein, is shown in Patent No. 1,149,174, dated August 10, 1915. Both the machine itself and the form of type-carrier

referred to are familiar to those skilled in the art, and for this reason and also for the 70 reason that the above mentioned patents may readily be referred to, it has been deemed unnecessary herein to illustrate or describe them in detail. Moreover such illustration

and description would be needlessly burdensome to this specification without assisting to form a complete understanding of the invention. For identifying purposes however

certain parts of the machine have been shown: for example, the mold A replaceably 75 mounted on the machine frame and comprising the cross-block *a* and the mold blade *a'*, the latter gaging the set-size of the type

during the casting and acting to eject the type after it has been cast and cooled, the 80 cross-block *a* being moved to open a side of the mold cavity to permit of such ejection;

the type carrier B; the fixed channel-block C; the movable or adjustable channel block D, the line channel being formed between 85 these blocks; the line hook E and the channel block screw F.

It will be understood that in a machine of this kind each type is individually cast in the mold cavity, the upper portion of which 90 cavity is surrounded by the matrix seat *a²*, the carrier B thereafter advances and the type is ejected by the mold blade *a'* to a

position between the jaws of the carrier; the carriers thereafter drawn in the opposite direction to a position in line with the type-channel formed between the channel 95 blocks C and D and a type pusher (not

105

70

75

80

85

90

95

105

shown) forces the type from between the jaws of the carrier into the type-channel. These movements are of course in every respect properly timed and gaged, so that 5 the machine may produce type in rapid sequence and deliver them into the type channel from which they are subsequently drawn by the line hook E and moved thereafter into the gallery or other receptacle of 10 the machine.

The type-carrier is moved forward and backward by means of a cam-operated lever to which the carrier is connected by the rod b'. The carrier at its forward end is provided with a fixed clamping jaw b² and a clamping jaw b³, movable relatively to the fixed jaw of the carrier. The operation of the movable jaw is accomplished by the lever b⁴ mounted upon the carrier and suitably 15 connected with the movable jaw, the lever being engaged by a stop 5, which as shown takes the form of a Z-shaped bar. The forward bent portion 5' of the bar is adapted to engage with the lever b⁴ to cause movement of the movable jaw of the carrier 20 against the resistance of the spring b⁵ shown in Fig. 3. This spring maintains the lever yieldably in a definite normal position shown in Figs. 1, 3 and 4 until by the 25 advance of the type-carrier the lever strikes the stop and is moved against the resistance of the spring, at the same time moving the movable jaw b³ of the carrier relatively to the carrier and to the machine frame. In 30 machines heretofore made and used the stop for the lever b⁴ was rigidly secured to the frame of the machine. According to the 35 present invention this rigid stop is replaced by the Z-shaped stop 5, and the carrier is provided with the abutment 6, secured to the type carrier at the connection between the body of the latter and the rod b'. This carrier abutment is adapted to engage with a 40 slide 7 mounted on the frame of the machine and having a projection 7' against which the abutment 6 of the carrier strikes at a definite point in its forward movement. The slide 7 also has a depending projection 7² to engage with the outer end of the connecting lever 8 45 to be described hereinafter. The slide 7 is provided with slots through which the securing screws 7³ pass, these slots permitting movement of the slide with respect to the frame. A spring 7⁴ secured at one end to the post 7⁵ on the slide and at the other end to the post 7⁶ fastened to the frame yieldably 50 maintains the slide in a definite rearward or normal position except when moved by the abutment 6. This spring is a stronger spring than the spring b⁵ previously referred to.

The connecting lever 8 and the connecting lever 9 form a pair of levers of equal length of which the lower lever 9 is pivotally secured 55 at its outer end 10 to the frame of the

machine and engages at its other inner end with the bent end portion 5² of the stop 5; at its center it is pivoted to the center of the upper lever 8, the outer end of which lever 8 over the pivot 10 is provided with a pin 11 70 for engagement with the bar 12 rigidly secured to the movable type block D. The opposite or inner end of the lever 8 engages with the depending projection 7² of the slide. In Fig. 1 both connecting levers are 75 in alignment, the type block being set for say, six point, type. In Fig. 2 where the point size adjustment is for approximately 12 point type, these levers are spread apart at their inner ends. The adjustment of the 80 channel block D acts through connecting means including the rod 12, the connecting levers 8, 9, and the yieldably mounted slide 7 to effect a positioning of the stop 5 corresponding to the adjusted position of the 85 channel block. During the advance of the type carrier the abutment 6 contacts with the projection 7' of the slide and moves the slide along with the type carrier. This permits the stop 5 to be advanced by the lever 90 b⁴ in unison with the carrier.

The adjustment of the channel block automatically causes through its connection with the stop 5 a corresponding adjustment of the latter relatively to the machine frame 95 and to the slide 7. The adjustment of the stop causes, in turn, an opening of the jaws of the type carrier corresponding with the point size adjustment of the type channel. Since the latter's adjustment corresponds 100 with the point size of the type bodies being cast in the mold, the type grasping jaws of the carrier are caused to be adjustably opened to correspond with such point size; moreover, the jaw adjustment, being connected with the type channel adjustment, 105 corresponds with the latter and is accomplished by the single adjustment of the movable channel block. This adjustment of the jaws is in practice somewhat wider than the point size of the types themselves so that the type carrier jaws will be opened wide enough to receive and carry the type without grasping them until the stop 5 and the lever b⁴ no longer control the movable type carrier jaw b³. This occurs in the rearward movement of the carrier when the stop 5 ceases to move; in other words, when the slide 7 moving rearwardly due to the action 110 of the spring 7⁴ as permitted to act by the rearward movement of the abutment 6 of the carrier and while so moving rearwardly pushing the inner ends of the connecting levers 8 and 9 and with them the stop 5 before it, has arrived at its normal position. 115 At this point in the rearward movement of the carrier, the jaws, and the type between them, have arrived at the approximate position shown in dot-and-dash lines in Fig. 1, in which the matrix seat a² of the mold 120

has been left behind. At such position the movable jaw b^3 begins to close on the type, due to the action of the spring b^5 and the type becomes firmly grasped and held between the jaws. While in proximity to the matrix seat or in the region thereof the type is confined but not grasped so that a kern or platform of the type resting on the matrix seat may be freely slid along said seat before being grasped by the carrier jaws and drawn rearwardly and, slightly downwardly, as shown in Fig. 3, toward the type channel. The provision of the slide and associated parts to maintain a definite opening of the jaws while in proximity to the matrix seat therefore prevents danger of type being mutilated during delivery to the type channel. The adjustability of the stop 5 to provide a point-size opening of the jaws to correspond with the point-size of the type being cast is likewise valuable to prevent type breakage or other mutilation and the connecting of this adjustment with the adjustment of the type channel prevents error in the stop adjustment and contributes toward the ready and easy control of the machine.

In adjusting the type channel block D the screw F is loosened and the block moved to make the channel wider or narrower, after which the screw F is tightened, this being the usual practice. If the channel is widened the bar 12 pushes against the pin 11 to move the outer end of upper connecting lever 8, the inner end of said lever resting against the depending projection 7^2 of the slide 7. The central portion of the lever where it is pivoted to the lever 9 is thus moved one-half the distance that the outer end of lever 8 has been moved; since the lever 9, pivoted to the frame at 10, is moved half the adjusting distance, its inner end will move the full distance and in the same direction as the movement of the outer end of the lever 8. In thus moving, the lever 9, by contact with the projection 5^2 of the stop 5, adjusts the stop so that its forward projection $5'$ is moved to correspond exactly with the adjustment of the channel block D. An adjustment of the channel block D to narrow the channel causes in effect a corresponding adjustment of the stop 5, as is apparent. This adjustment may not take place simultaneously with the adjustment of the block but will be accomplished on the forward movement of the carrier B relatively to the frame of the machine, the lever b^4 of the carrier striking against the projection $5'$ of the stop and sliding it to move the connecting levers 8 and 9 until the pin 11 of the lever 8 has come against the end of the bar 12, if it has not already done so due to the action of the lever spring b^6 . In any adjustment of the block the stop adjustment automatically corresponds with the

block adjustment; the stop is thus adjusted in fixed position relatively to the machine frame and to the slide.

Further forward movement of the carrier will move the lever b^4 on its pivot and against the resistance of its spring b^5 , since the stop 5 is fixed in adjusted position. This lever movement operates in the well-known manner to move the carrier jaw b^3 to cause an opening of the jaws. This opening reaches its maximum, which maximum is slightly more than the point-size of the type being cast, when the carrier has reached approximately the dot-and-dash position of Fig. 1; in other words, when the jaws have reached the region of or are in proximity to the matrix seat a^2 of the mold A. At this point the abutment 6 of the carrier strikes the upstanding projection $7'$ of the slide 7 so that during the rest of the movement of the carrier the slide moves in unison with the carrier. This movement of the slide, against its spring 7^4 , allows the inner end of connecting lever 8 to move and such movement is brought about by the lever b^4 pushing the stop 5 so that its projection 5^2 acts upon the connecting levers to maintain the inner end of lever 8 against the projection 7^2 of the slide 7. Thus, when the region of the matrix seat is reached, the slide is moved together with and at the same speed as the carrier and this allows the stop to be moved similarly and in unison with the slide; the result is that the carrier jaws do not open further nor do they close but maintain the determined degree of opening to the end of the forward stroke of the carrier.

After the type T has been pushed by the blade a' between the carrier jaws, the position of the carrier being that shown in Fig. 2, the carrier is caused to move rearwardly. Until the region of the matrix seat has been passed the jaws will be maintained open, so that the type is sufficiently free to move vertically in the jaws, as may be required if the type is provided with a kern or other portion projecting over the matrix seat. When this region has been passed, there is no danger of mutilating the type, and the slide 7 having come to rest in its normal definite or retracted position, the stop 5 is halted in its rearward movement and the lever b^4 is permitted to move forward under the action of its spring, thus causing the carrier jaw b^3 to move toward the fixed jaw b^2 thereof to grasp the type. The movement of the carrier continues to the full line position shown in Fig. 1 and the type is ready to be ejected into the type channel by the type pusher. It will be observed that the rearward movement of the stop 5 and of the slide 7 is accomplished by the slide spring 7^4 and that this spring must be stronger than the lever spring b^5 to permit of the proper operation of the device. It is also to be noted that a

definite opening of the type carrier jaws is maintained in proximity to the matrix seat on the mold during both the forward and the rearward travel of the carrier and that 5 the connecting levers 8 and 9 form an adjustable connection between the slide 7 and the stop 5, this connection being adjusted as shown by adjusting the channel block D and its bar 12.

10 I claim:—

1. Type delivery mechanism comprising a supporting frame, a type carrier movable relatively to said frame, said carrier being provided with a clamping jaw movable relatively to the carrier and a lever operatively connected with said jaw, a stop for engaging with said lever to cause movement of the jaw, a slide mounted on the frame and having a projection, an abutment carried 15 by the carrier to engage with said slide, said stop being adjustable with respect to said slide and movable in unison therewith.

2. A typographic machine comprising a supporting frame, a type carrier movable 25 relatively to said frame, said carrier being provided with a clamping jaw movable relatively to the carrier, means for operating said jaw comprising a lever and a stop, an adjustable channel block and means connecting said block with said stop whereby adjustment of the block causes automatically 30 an adjustment of the stop.

3. A typographic machine comprising a supporting frame, a mold secured thereon 35 and having a matrix seat, a type carrier movable relatively to said frame, said carrier being provided with a fixed clamping jaw and with a clamping jaw movable relatively to the fixed jaw, a lever operatively 40 connected with said movable jaw, a spring to yieldably maintain the lever in a definite position, a stop for engaging with the lever to cause movement of the said movable jaw against the resistance of said spring, an 45 adjustable channel block, a bar secured to said block, a slide mounted on the frame, a spring stronger than the first mentioned spring to yieldably maintain said slide in a definite position, a connecting lever engaged at one end by the bar and at the other end by the slide, a second connecting 50 lever pivoted centrally to the first mentioned connecting lever and pivoted at one end to

the frame and engaging the stop at its other end, and an abutment on the carrier for engaging the slide whereby an adjustment of the channel block causes a corresponding adjustment of the stop to correspondingly open the clamping jaws, the carrier abutment and slide maintaining such opening of the said 60 jaws while the jaws are in proximity to the matrix seat.

4. A typographic machine comprising a supporting frame, a mold secured thereon and having a matrix seat, a type carrier 65 movable relatively to said frame, said carrier being provided with a fixed clamping jaw and with a clamping jaw movable relatively to the fixed jaw, a lever operatively connected with said movable jaw, a spring 70 to yieldably maintain the lever in a definite position, a stop for engaging with the lever to cause movement of the said movable jaw against the resistance of said spring, a slide mounted on the frame, a spring stronger 75 than the first mentioned spring to yieldably maintain the slide in a definite position, an abutment on the carrier for engaging with the slide to move it against the resistance of the second mentioned spring, and an adjustable connection between the slide and the stop, whereby adjustment of this connection causes a definite opening between the carrier jaws and the movement of the slide by the carrier abutment maintains said opening 80 while the jaws are in proximity to the matrix seat of the mold.

5. Type delivery mechanism comprising a supporting frame, a type carrier movable relatively to said frame, said carrier being provided with a fixed clamping jaw, a clamping jaw movable relatively to the carrier and a lever operatively connected with said movable jaw, a stop for engaging with said lever to open said jaws, an adjustable 90 channel block, means connecting said block with said stop and including a slide mounted on the frame, whereby adjustment of said block causes automatically an adjustment of the stop to correspondingly open the clamping jaws, and an abutment on the carrier to engage with the slide to maintain during 95 such engagement the opening of the jaws determined by the stop adjustment.

MAURITZ C. INDAHL.
